ABSTRACT OF THE DISCLOSURE

A water-soluble surface active detergents are provided which have a low foaming tendency and good cleansing power, containing (A) a water-soluble surface-active ethylene oxide adduct having good cleansing power and a high foaming tendency and (B) a water-insoluble water-dispersible surface-active dialkylphenol-ethylene oxide adduct having a low-foaming tendency and relatively poor cleansing power, in an amount to reduce the foaming tendency of (A) without substantially adversely affecting the cleansing power of (A).

This invention relates to a washing and cleansing composition having low foaming tendency and high detergative power.

Detergents used for washing in modern washing machines are required to show in addition to good detergative power also a very low foaming tendency within the entire temperature range (20–100° C.) used in machine washing, since otherwise there will be the risk of overfoaming which may damage the washing machine. This latter property is of particular importance in connection with certain detergents at lower washing temperatures, i.e., at temperatures below 60° C., and when the laundry to be washed is only very slightly soiled. The foam proper does not contribute to the washing effect of the detergent either.

It is previously known to incorporate in detergents as an active component water-soluble alkylene oxide adducts of hydroxy group containing substances, such as mono- or dialkylphenols, oxo alcohols or fatty alcohols, or mixtures thereof. Such alkylene oxide adducts have also been mixed with alkylarylsulphonates and with soap, in which case the soap acts mainly as a foam reducing agent. There are also previously known particularly low foaming water-soluble alkylene oxide adducts obtained by adding ethylene oxide and propylene oxide to various hydroxy group containing substances. Due to their high price these adducts have not been used to a greater extent, however. None of the known compositions renders the desired low foaming tendency without at the same time substantially reducing the detergative power.

The present invention relates to a low-foaming washing and cleansing composition which does not show the aforesaid disadvantages but produces very little foam within the entire temperature range used in machine washing at the same time as a highly satisfactory detergative power is obtained. The washing and cleansing composition according to the invention comprises as a surface-active component a water-soluble mixture of (A) a water-soluble surface-active ethylene oxide adduct of a polypropylene glycol having a minimum molecular weight of 1000, a primary or secondary straight or branched chain aliphatic alcohol having 8 to 24 carbon atoms, or a mono-, di- or tri-substituted alkylphenol having a total of 8 to 24 carbon atoms in the alkyl portion, in combination with

2

(B) a water-insoluble but water-dispersible surface active dialkylphenol ethylene oxide adduct having the general formula

wherein R₁ and R₂ are straight or branched chain alkyl substituents having 8 to 12 carbon atoms, and n is a figure indicating the number of ethylene oxide units up to which the product is water-insoluble but water-dispersible. The combination of the substances A and B above has surprisingly proved to bring about the effect that component B which is only water-dispersible, extremely low foaming and of poor detergative power becomes water-soluble while maintaining its low-foaming properties at the same time as the detergative power of the resulting mixture becomes good and usually better than the detergative power of each individual component A or B.

10 15 20 25

The water-soluble surface-active ethylene oxide adduct comprised in the composition according to the invention may be an ethylene oxide adduct of a polypropylene glycol having a minimum molecular weight of 1000 and the general formula

wherein a, b and c have such values that the ethylene oxide content in the adduct amounts to 20–90%. Examples 30 are the products sold by Wyandotte Chemical Corporation under the name Pluronic®

35 40 45

Other suitable water-soluble surface-active ethylene oxide adducts which may be used in the composition according to the invention are adducts of ethylene oxide and primary or secondary, straight or branched chain aliphatic alcohols having a total of 8 to 24 carbon atoms in the molecular chain, for example ethylene oxide adducts of the fraction of fatty alcohols which is obtained at the hydrogenation of oils, such as coconut oil, or tall oil, or by hydrolyzing whale fat, or ethylene oxide adducts of dodecyl alcohol, cetyl alcohol, oleyl alcohol and stearyl alcohol, or oxo alcohols, such as tridecyl alcohol, hexadecyl alcohol and the like, or mixtures thereof. A suitable amount of ethylene oxide to be added to the fatty alcohol are 5–100 moles per mole of fatty alcohol.

50 55 60

Other suitable water-soluble surface-active ethylene oxide adducts are adducts of ethylene oxide and mono-, di- or trisubstituted alkylphenols having a total of 8 to 24 carbon atoms in the alkyl portion, such as octylphenol, dioctylphenol or trioctyl phenol, nonylphenol, dinonylphenol, dodecylphenol, didodecylphenol, tributylphenol, methyldibutylphenol.

A suitable amount of ethylene oxide to be added to the alkylphenol are 7–100 moles per mole of alkylphenol. Examples of such products are the products sold under the names Triton X-100 (Rohm & Haas), Lissapol N (ICI), Igepal (Antara), Hostapal (Hoechst), LANCO (Berol).

65 70

The water-insoluble but water-dispersible component is an ethylene oxide adduct having the general formula

wherein R₁ and R₂ are straight or branched chain hydrocarbon substituents having 8 to 12 carbon atoms, and n is a figure indicating the number of ethylene oxide units up to which the product is water-insoluble. A water-in-

soluble but water-dispersible product is in this connection to be understood such, that the product in question when being diluted with water of 18° C. to an 1% concentration shall result in a dispersion, i.e. not a clear solution but a turbid liquid. The suitable number of ethylene oxide groups, of course, depends to some extent on the number of carbon atoms in the alkyl portion of the dialkylphenol. Usually from 8 to 20, preferably from 10 to 16 ethylene oxide units are the suitable number. Examples of suitable water-insoluble but water-dispersible dialkylphenol ethylene oxide adducts are the following, the amount of added ethylene oxide (EO) being indicated within parenthesis: dinonylphenol (9 to 14 moles of EO) wherein the nonyl portion originates in propylene trimer, dialkylphenol (9 to 15 moles of EO) wherein the alkyl portion originates in a linear alpha-olefin mixture having 8 to 12 carbon atoms (straight chain), branched chain diethylphenol (10 to 14 moles of EO), didodecylphenol (14 to 20 moles of EO).

The ratio by weight of component A to component B in the washing and cleansing composition according to the invention is from 1:9 to 1:1, preferably from 1:3 to 1:2.

Furthermore it has been found according to the invention that the foaming capacity can be reduced still more while maintaining or improving the detergent power by adding (C) a further water-insoluble but water-dispersible ether adduct having the general formula

wherein X designates a monoalkyl group having 8 to 24 carbon atoms, a monoalkylaryl group having 8 to 16 carbon atoms in the alkyl chain, a dialkylaryl group having a total of 12 to 24 carbon atoms in the alkyl chains or a trialkylaryl group having a total of 8 to 24 carbon atoms in the alkyl chains, and n designates the number of ethylene oxide units up to which the product is water-insoluble but water-dispersible. The addition of this third component C is particularly advantageous for the washing at lower temperatures, such as between 40 and 60° C.

Compounds having the above formula which are particularly suitable are alkylether adducts having straight or branched chains and 12 to 22 carbon atoms in the alkyl chain, for example ethoxylated fatty alcohols, monoalkylphenol ethylene oxide adducts, dialkylphenol ethylene oxide adducts and trialkylphenol ethylene oxide adducts. The suitable amount of ethylene oxide to be added in order to obtain a water-insoluble but water-dispersible product varies from 2 to 25 moles and is to be determined

Example 1

75 parts by weight of a water-insoluble dinonylphenol ethylene oxide adduct containing 12 moles of ethylene oxide and the alkyl chains originating in propylene trimer were mixed with 25 parts by weight of a tallow fatty alcohol-ethylene oxide adduct containing 30 moles of ethylene oxide. The resulting mixture was water-soluble.

15 parts by weight of the mixture were mixed with a builder and with water to form a detergent having the following composition and being suitable for machine washing:

	Percent
Adduct mixture	15
Sodium tripolyphosphate	35
15 Anhydrous sodium carbonate	15
Sodium silicate 38/40° Bé. $Na_2O/SiO_2 = 1:25$	15
Sodium sulphate	8
Sodium carboxymethylcellulose (Cellufix LB)	2
Water	10

The sodium perborate (bleaching agent) which normally would have been comprised in the formulation was exchanged against water, so that the washing effect could be attributed only to the adduct mixture used.

25 The foaming capacity of the detergent at 75° C. and 40° C. was determined according to the so-called shake test at a concentration 4.75 g./l. and 300 p.p.m. (~17.6° dH) water hardness. The foam determination according to this method is carried out such, that a 500 ml. cylinder is filled with 200 ml. of detergent solution of the indicated temperature and concentration whereupon shaking is effected by rotation causing the cylinder to make 10 revolutions in 15 seconds. The foam level in the cylinder is read off immediately and after 5 minutes.

35 In addition, the deteritive power was determined in a Terg-O-Tometer, at 85° C. using an artificially soiled cotton fabric at a concentration of 2.5 g./l. and 300 p.p.m. water hardness. The reflectance of the fabric before and after the washing was determined in a reflectometer. 40 Corresponding determinations were made individually with the water-insoluble and water-soluble adduct in combination with the builders.

The results obtained appear from Table 1 below. (In this and the following tables DNF designates dinonylphenol, TFA designates tallow fatty alcohol and DAF designates dialkylphenol. EO designates ethylene oxide and the figure preceding EO is the number of moles of ethylene oxide units added to the nonylphenol or tallow fatty alcohol.)

TABLE 1

				80	81.9

in each individual case. Examples of such suitable water-insoluble but water-dispersible ether adducts are nonylphenol+4 EO, didecylphenol+14 EO, tallow fatty alcohol+6 EO, etc.

When component C is used in the compositions according to the present invention the amount of component A in relation to the total amount of components B and C should be from 1:9 to 1:1, preferably from 1:3 to 1:2.

The invention is illustrated by the following examples. The alkylphenols indicated in the examples were prepared by reacting phenol with olefins using boron trifluoride as a catalyst. The addition of ethylene oxide was effected in a known manner in the presence of an alkaline catalyst.

65 As appears from Table 1 the composition according to the invention showed an improved washing effect as compared with the deteritive power of each individual component. At the same time, the foaming capacity was small.

Examples 2-6

In the same manner as in Example 1 the foaming capacity and the deteritive power were determined for detergents, the adduct mixture of which was composed of a water-insoluble dinonylphenol ethylene oxide adduct and a water-soluble ethylene oxide adduct in such an amount that this mixture became water-soluble. The results are indicated in Table 2. As from Example 1 it appears from

Examples 2-6 that according to the invention a detergent is obtained having substantially reduced foaming capacity at the same time as the high deterutive power of the water-soluble ethylene oxide adducts is maintained or improved.

Examples 11 and 12

A water-insoluble dialkylphenol ethylene oxide adduct (DAF) with 14 moles of ethylene oxide and side chains

Examples 7-10

In the same manner as in Example 1 the foaming capacity and deterutive power were determined at 40° C. for detergents, the adduct mixture of which was composed of 30 a water-insoluble dinonylphenol ethylene oxide adduct

originating in a straight chain alpha-olefin mixture containing 8 to 12 carbon atoms was investigated with respect to foaming capacity at 75° C. and with respect to deterutive power at 85° C. in the same manner as in Example 1. The results are shown in Table 4.

TABLE 4

and a water-soluble ethylene oxide adduct in such an amount that this mixture became water-soluble. For the 50 determination of the deterutive power at this low temperature 4 g./l. of the detergent were used. The results appear from Table 3.

The examples show that the invention may be applied also to unbranched dialkylphenol derivatives originating in alpha-olefins and that the same advantageous results are obtained.

Examples 13-18

The examples show that detergents composed according to the invention render the desired foam reduction even at low temperature, while maintaining or improving the washing effect.

The following further experiments were carried out to show the effect of adduct mixtures containing at most 20% of alkylphenol adducts and the remainder fatty alcohol adducts.

TABLE 5

Ex. No.	Percent						Foam level in mm.				Soil removal, percent	
	DNF, 9 EO	DNF, 10 EO	DNF, 12 EO	DNF, 14 EO	TFA, 4 EO	DNF, 4 EO	TFA, 50 EO	40° C.	60° C.	40° C.	60° C.	
13.....	15				35		50	30	25	45	40	57.6

17.....				40		30	30	30	25	30	25	60.7
18.....						100	80	20	85	25	25	56.4

The foam tests were carried out at 300 p.p.m.=17.6° dH; conc. 4.75 g./l. at 40° C. and 75° C.

The washing tests were carried out at 270 p.p.m.=15° dH; conc. 5 g./l. at 40° C.; 3 g./l. at 85° C.

Composition used in the foam tests:

Percent

Adduct mixture	10
Na-tripolyphosphate	35
Na-carbonate	15
Na-sulphate	8
Na-CMC	2
Na-water glass	15
Water	10

Composition used in the washing tests:

Percent

Adduct mixture	10
Na-tripolyphosphate	35
Na-carbonate	15
Na-sulphate	9
Na-CMC	2
Water glass	14
Water	10

From Examples 13-16 it thus appears that even with a content of up to 20% of biologically hard surface active substances (dinonylphenol adducts) low foam levels are obtained without the washing capacity being materially lowered.

The use of an adduct mixture containing the three components A, B and C mentioned above is illustrated by the following examples in which the detergents used were composed as follows:

	Percent
Surface active components (A, B, C)	15
Sodium polyphosphate	35
Anhydrous sodium carbonate	15
Sodium silicate 38/40° Bé. $\text{Na}_2\text{O}/\text{SiO}_2 = 1:2.4$	15
Sodium sulphate	8
Sodium carboxymethylcellulose (Cellufix LB)	2
Water	10

The results obtained appear from the Tables 6, 7 and 8.

TABLE 6

The Examples 19-25 show that the addition of the third component C substantially reduces the foaming capacity at the same time as the deterging power of the composition is maintained or improved. Example 25 shows a comparative test with a composition having a two-component adduct mixture and a composition having a three-component adduct mixture at low temperatures (40 and 60° C.). It appears from this example above all that at such a low temperature as 40° C. the immediate foam formation is reduced to $\frac{1}{3}$ by the addition of the third water insoluble but water-dispersible component C.

What we claim is:

1. A water-soluble surface-active detergent having a low foaming tendency and good cleansing power, consisting essentially of (A) a member selected from the group consisting of water-soluble surface-active ethylene oxide adducts of a polypropylene glycol having a molecular weight of at least 1000, the ethylene oxide content in the adduct being within the range from about 20 to about 90%, primary and secondary aliphatic alcohols having from about eight to about twenty-four carbon atoms containing from about 4 to about 100 moles of ethylene oxide, and alkylphenols having from about eight to about twenty-four carbon atoms in the alkyl group and from one to three alkyl groups containing from about 7 to about 100 moles of ethylene oxide, in combination with (B) a water-insoluble water-dispersible surface-active dialkylphenol-ethylene oxide adduct having the formula

wherein R_1 and R_2 are selected from the group consisting of alkyl groups having from about eight to about twelve carbon atoms, and n is a number within the range from about eight to about twenty, in an amount to reduce the foaming tendency of (A) without substantially adversely affecting the cleansing power of (A).

2. A water-soluble surface-active detergent in accordance with claim 1 wherein (A) is an ethylene oxide adduct of a polypropylene glycol having the general formula

wherein a , b , and c are sufficiently large to provide an ethylene oxide content in the adduct within the range from about 20 to about 90% of the adduct.

3. A detergent composition having low foaming tendency and good cleansing power consisting essentially of a water-soluble surface-active combination in accordance with claim 1 and water.

4. A detergent composition in accordance with claim 1 containing, in addition, an inorganic builder.

5. A detergent composition in accordance with claim 1 containing, in addition, sodium perborate as a bleaching agent.

6. A water-soluble surface-active detergent in accordance with claim 1 wherein (A) is a tallow fatty alcohol-ethylene oxide adduct (B) is a dinonylphenol-ethylene oxide adduct.

7. A water-soluble surface-active detergent in accordance with claim 1 wherein (A) is a nonylphenol-ethylene oxide adduct and (B) is a dinonylphenol-ethylene oxide adduct.

8. A water-soluble surface-active detergent in accordance with claim 1 wherein (A) is a lauryl alcohol-ethylene oxide adduct (B) is a dinonylphenol-ethylene oxide adduct.

9. A water-soluble surface-active detergent in accordance with claim 1 wherein (A) is a block polymer comprising 20% polypropylene glycol of molecular weight 1750 and 80% ethylene oxide and (B) is a dinonylphenol-ethylene oxide adduct.

10. A water-soluble surface-active detergent in accordance with claim 1 wherein (A) is a 3-methyl-4,6-dibutyl-

phenol-ethylene oxide adduct containing 12 moles of ethylene oxide and (B) is a dialkylphenol-ethylene oxide adduct containing 14 moles of ethylene oxide and side chains originating in a straight chain alpha olefin mixture containing from eight to twelve carbon atoms.

5 11. A water-soluble surface-active detergent in accordance with claim 1 wherein (A) is a dodecyl-phenol-ethylene oxide adduct containing 13 moles of ethylene oxide and (B) is a dialkylphenol-ethylene oxide adduct containing 14 moles of ethylene oxide and side chains originating in a straight chain alpha olefin mixture containing from eight to twelve carbon atoms.

10 12. A water-soluble surface-active detergent in accordance with claim 1 containing, in addition, (C) a water-insoluble water-dispersible ethylene oxide ether adduct having the formula

wherein X is a member selected from the group consisting of alkyl groups having from about eight to about twenty-four carbon atoms, alkylphenyl groups having from about eight to about sixteen carbon atoms in the alkyl chain, dialkylphenyl groups having a total of from about twelve to about twenty-four carbon atoms in the alkyl chains, and trialkylphenyl groups having a total of from about eight to about twenty-four carbon atoms in the alkyl chains, and n is a number within the range from about two to about twenty-five sufficient to provide water-insolubility and water-dispersibility.

20 13. A water-soluble surface-active detergent in accordance with claim 12 wherein (C) consists essentially of an ethoxylated fatty alcohol having from about twelve to about twenty-two carbon atoms in the alkyl group.

25 14. A water-soluble surface-active detergent in accordance with claim 12 wherein (C) consists essentially of an ethylene oxide adduct of a monoalkylphenol having from about eight to about fifteen carbon atoms in the alkyl chain.

30 15. A water-soluble surface-active detergent in accordance with claim 12 wherein (A) is a tallow fatty alcohol-ethylene oxide adduct containing 50 moles of ethylene oxide, (B) is a dinonylphenol-ethylene oxide adduct containing 14 moles of ethylene oxide and (C) is a nonylphenol-ethylene oxide adduct containing 4 moles of ethylene oxide.

35 16. A water-soluble surface-active detergent in accordance with claim 12 wherein (A) is a dinonylphenol-ethylene oxide adduct containing 21 moles of ethylene oxide, (B) is a dinonylphenol-ethylene oxide adduct containing 14 moles of ethylene oxide and (C) is a nonylphenol-ethylene oxide adduct containing 4 moles of ethylene oxide.

40 17. A water-soluble surface-active detergent in accordance with claim 12 wherein (A) is a tallow fatty alcohol-ethylene oxide adduct containing 50 moles of ethylene oxide, (B) is a dinonylphenol-ethylene oxide adduct containing 12 moles of ethylene oxide and (C) is a dodecylphenol-ethylene oxide adduct containing 14 moles of ethylene oxide.

45 18. A water-soluble surface-active detergent in accordance with claim 12 wherein (A) is a fatty alcohol containing from about twelve to about eighteen carbon atoms-ethylene oxide adduct containing 7 moles of ethylene oxide, (B) is a dinonylphenol-ethylene oxide adduct containing 12 moles of ethylene oxide and (C) is a tallow fatty alcohol-ethylene oxide adduct containing 6 moles of ethylene oxide.

50 19. A water-soluble surface-active detergent in accordance with claim 12 wherein (A) is a nonylphenol-ethylene oxide adduct containing 10 moles of ethylene oxide, (B) is a dinonylphenol-ethylene oxide adduct containing 14 moles of ethylene oxide and (C) is a nonylphenol-ethylene oxide adduct containing 4 moles of ethylene oxide.

UNITED STATES PATENT OFFICE
CERTIFICATE OF CORRECTION

Patent No. 3,429,822 Dated February 25, 1969

Inventor(s) Helmut Grunewald and Ake Waag

It is certified that error appears in the above-identified patent and that said Letters Patent are hereby corrected as shown below:

- Column 1, line 15, "A water" should be -- Water --;
line 50, "also" should be -- also --.
Column 2, line 31, A period (.) should be inserted at the end of the line.
Column 3, line 27, "dispensible" should be -- dispersible --.
Column 4, line 16, "1:25" should be -- 1:2.4 --.
Column 6, Table 4, "3-methyl-4, 6-dibutylphenol Elus 12 EO." should be -- 3-methyl-4, 6-dibutylphenol plus 12 EO. --
Column 8, Table 6, last heading, "Increasen" should be -- Increase in --.
Column 9, line 59 (Claim 6), "and" should be inserted after "adduct";
line 67 (Claim 8), "and" should be inserted after "adduct".
Column 11, line 3, (References cited) "3,034,839" should be -- 3,034,989 --;
line 5, "Grefo" should be -- Grifo --.
